UNITED STATES PATENT OFFICE

167,266

ELECTRIC SOLDERING IRON

Walter A. Kuehl, Chicago, Ill.

Application February 28, 1952, Serial No. 18,705

Term of patent 14 years

(Cl. D26—1)

To all whom it may concern:

Be it known that I, Walter A. Kuehl, a citizen of the United States, residing at Chicago, Cook County, State of Illinois, have invented a new, original, and ornamental Design for an Electric Soldering Iron, of which the following is a specification, reference being had to the accompanying drawing forming a part thereof, wherein Fig. 1 is a side view of an electric soldering iron embodying my new design; Fig. 2 is a top view of the electric soldering iron; Fig. 3 is a top view of the electric soldering iron with the tip protecting cover removed and Fig. 4 is a front view of the electric soldering iron with the tip protecting cover removed.

I claim:

The ornamental design for an electric soldering iron, as shown.

WALTER A. KUEHL.
